SCREEN DEVICE FOR WINDOWS

Filed Aug. 3, 1928

UNITED STATES PATENT OFFICE

EMIL WILKING, OF CHICAGO, ILLINOIS

SCREEN DEVICE FOR WINDOWS

Application filed August 3, 1928. Serial No. 297,366.

The invention relates generally to window structures. More particularly the invention relates to that type of window structure which comprises a frame having a pair of sashes or panels slidably mounted therein and is associated with a device which is adapted to be used in lieu of the ordinary or usual wire screen and comprises a spring actuated roller on the window-frame and a flexible fabric screen which is wound around the roller and is attached to the sash or panel so that it will be unwound from the roller and bridge or cover the window opening when the sash is shifted into any of its open positions.

One object of the invention is to provide a window structure of the aforementioned type in which the screen device is associated with the outer sash or panel and is mounted on the inside part of the window frame so that it is protected when the sash is in its closed position.

Another object of the invention is to provide a window structure of the character hereunder consideration which is generally of new and improved construction and is an improvement upon previously designed structures for the same purpose.

Other objects of the invention and the various advantages and characteristics of the present construction will be apparent from a consideration of the following detailed description.

Other objects of the invention and the various advantages and characteristics of the present construction will be apparent from a consideration of the following detailed description.

The invention consists in the several novel features which are hereinafter set forth and are more particularly defined by the claims at the conclusion hereof.

In the drawing which accompanies and forms a part of this specification or disclosure and in which like numerals and characters of reference denote corresponding parts throughout the several views:

Figure 1 is a front elevational view of a window in which the upper and lower glass-

bearing panels are each provided with a screen device;

Figure 2 is a vertical sectional view taken on the line 2—2 of Figure 1; and

Figure 3 is a horizontal section taken on the line 3—3 of Figure 1.

The window structure which forms the subject matter of the invention embodies an inner panel *a* and an outer panel *b*. These panels are mounted in a frame *c* so that they are vertically offset with respect to each other and are shiftable into overlapping relation to uncover the upper and lower parts of the window opening (see Figures 1 and 2). The panel *a* consists of a pane *a'* of glass or similar transparent material and a rectangular sash or casement *a*² in which the pane *a'* is mounted and is held in place by any suitable sealing material or means. The sash *a*² consists of a bottom crossbar *a*³, side bars *a*⁴ and an upper crossbar *a*⁵. The panel *b* is similar in construction to the panel *a* and comprises a glass pane *b'* and a rectangular sash *b*² in which the pane is mounted. The panel *a* is disposed inwardly of the panel *b* and is adapted normally to close the lower half of the window opening which is formed by the frame *c*. The latter consists of a bottom member *c*', side members *c*² and a top member *c*³. The panel *a* is guided and held within the window-frame *c* so that it may be raised by vertical shift movement into its open position, by a pair of vertically extending guide strips *c*⁴ and a pair of vertically extending guide strips *c*⁵. The guide strips *c*⁴ are imbedded in the central parts of the side members *c*² of the window frame and project toward each other so as to form guide surfaces for engaging the outer faces of the side bars *a*⁴ of the sash *a*². The strips *c*⁵ are disposed inwardly of the strips *c*⁴ and are secured in place so that the outer edges thereof form guide surfaces for engaging the inner faces of said side bars of the sash *a*². The panel *b* is adapted to cover the upper half of the window opening and consists of a lower crossbar *b*³, side bars *b*⁴ and an upper crossbar *b*⁵. This panel *b* is held in place so that it may be lowered or raised, by a pair of

100

vertically extending guide strips c^6 . The latter are secured to the side members c^2 respectively and form guide surfaces for the outer faces of the side bars of the sash b^2 . The inner faces of said last mentioned side bars fit against the guide strips c^6 . Handles a^6 for use in raising and lowering the panel a are secured to the inner face of the lower cross bar a^8 . The panel a is counterbalanced so that it will remain in any of its open positions by a pair of weights a^7 which are disposed in vertically extending compartments a^8 . The latter are formed by the side members c^2 of the window-frame and the contiguous parts of the surrounding building structure. The weights are connected to the upper ends of the side bars a^4 of the sash a^2 by flexible cables a^9 which extend upwardly and pass over pulleys or sheaves a^{10} . These pulleys are pivotally mounted on pins a^{11} which are mounted in the side members c^2 of the frame. The panel b is counterbalanced by means of a pair of weights b^6 which are disposed in the compartments a^8 . Flexible cables b^7 which pass over sheaves b^8 connect these weights with the upper ends of the side bars b^4 . A molding c^7 is secured to the inner face of the window frame c for ornamental purposes. Beneath the bottom member c' is a ledge c^8 which projects outwardly and forms a sill, as well understood in the art. As described so far, the window is of standard or conventional construction and exemplifies the type of construction now used for buildings and like structures.

The invention contemplates the provision of a device 14 which is adapted to prevent the entry of dust through the bottom part of the window opening when the panel a is in any of its open positions and a device 15 which is adapted to arrest dust from entering the upper part of said opening. The device 14 comprises a roller 16 and a flexible screen 17 which is wound around the roller and is attached to the crossbar a^8 of the sash a^2 so that it will be unwound and bridge or close the window opening when the panel a is lifted into any of its raised positions. The screen 17 is preferably formed of loosely woven fabric and serves to arrest dust particles and permit air to pass through the opening for ventilating purposes. The screen is of such width that the side margins thereof extend substantially to the side members c^2 of the window-frame c . The roller 16 is mounted in close proximity to the bottom member c' and is rotated by a helical spring (not shown) so that it automatically winds the screen thereon when the panel a is lowered into its closed position. The spring is mounted in an elongated chamber which extends longitudinally through the central portion of the roller. The ends of the roller are sup-

ported rotatably by a pair of sheet metal brackets 19 and 20. These brackets fit against the lower ends of the side members c^2 of the window-frame and are arranged so that the lower edges thereof abut against the bottom member c' . When the panel a is raised, the flexible screen 17 will be unwound from the roller and will cause the latter to rotate in a direction which results in winding of the spring. When the panel is lowered, the spring causes rotation of the roller in the opposite direction and automatically winds the screen back in place. The inner end of the screen 17 is secured or anchored to the roller by any suitable means. The outer end of the roller extends outwardly towards the ledge c^8 and then upwardly around a guide roll 67. This roll is connected pivotally to and supported by the brackets 19 and 20. The extreme outer end of the screen 17 is doubled back upon itself and is sewed as at 45 to form a hem 46. A stay 47 extends through this hem and is coterminous therewith. It is removably held in place against the crossbar a^8 of the panel a by a pair of retaining devices 48 so that the outer or distal end of the screen is connected removably to the sash a^2 of the panel. The retaining devices 48 are connected to the crossbar a^8 by screws 49 and embody upwardly extending fingers 48^a for securing releasably the stay 47 to the sash a^2 . Dust or dirt is prevented from passing between the side margins of the screen 17 and the sides of the window-frame by means of a pair of guide elements 52. The latter comprise fixed members 53 and hinged members 54. The fixed members are secured to the side member c^2 of the window-frame directly above the brackets 19 and 20 and embody inwardly extending right angle flanges 53^a which are adapted to lap the outer faces of the side margins of the screen. The hinge members 54 embody right angle flanges 54^a which are adapted to lap the inner faces of the side margins of the screen 17. Latches 55 serve to secure the hinged members in their operative position. When these latches are released, the hinged members may be swung inwardly so as to swing the flanges 54^a out of engagement with the contiguous faces of the side margins of the screen.

The screen device 15 which is associated with the panel b and the upper cross member c^8 of the window-frame is similar in construction to the device 14. It comprises a spring actuated roller 56 and a loosely woven fabric screen 57. The latter is wound around the roller 56 and has the outer end thereof connected by retaining devices 58 to a channel member 60 which is secured to the inner face of the crossbar b^8 by screws 61. When the panel b is lowered, the screen 57 is unwound from the

roller 56 and is drawn downwardly by the member 60 so that it extends alongside of the strip c^5 and closes the gap or opening at the top of the frame. When the panel b is raised into its closed position, the screen is rewound by the action of the roller 56. The channel members 60 projects inwardly from the crossbar b^5 across the path of travel of the panel a and is in the nature of a stop which limits the upward movement of said panel a . A characteristic and an advantage of mounting the screen device 15 for the outer panel on the inside part of the window-frame and utilizing the panel member 60 is that the device 15 is protected when the panel b is in its closed position and provision is made for preventing the inner panel from being shifted upwardly past the outer panel. The spring actuated roller 56 of the device 15 is supported rotatably by brackets 62. The latter are connected to the upper ends of the side members c^2 . Dust is precluded from passing around the side margins of the screen 57 by means of guide elements 63. The latter are similar in construction to the elements 52 and are mounted on the strips c^5 in alignment with said elements 52.

To prevent dust and other undesirable particles from passing between the panes a' and b' when the panels a and b are in their open position, a strip 64 is provided. This strip is secured to the bottom face of the lower crossbar b^3 of the sash b^2 and is provided with a strip 66 of felt or similar material which is adapted to fit against the pane a' .

The window construction disclosed and illustrated herein is exceedingly efficient in operation and serves effectively to prevent the entry of dust through the window opening. By virtue of the fact that both screen devices are mounted on the inside of the window, the flexible screens 17 and 57 are not subjected to snow and rain when the panels a and b are in their closed position.

The invention is not to be understood as restricted to the details set forth, since these may be modified within the scope of the appended claims, without departing from the spirit and scope of the invention.

Having thus described the invention, what I claim as new and desire to secure by Letters Patent, is:

55 1. In a screened window structure embodying a rectangular frame, an inner and an outer panel mounted slidably in the frame and adapted to be shifted into lapped relation, a spring actuated roller disposed at one end of the frame and inwardly of the inner panel, and a flexible screen wound around the roller; a member connected to the outer panel and projecting inwardly therefrom across the path of movement of the inner panel, said member being attached

to the free end of the screen and adapted, during shift of the outer panel, to unwind the screen from the roller and move it in a rectilinear path adjacent to the inner part of the frame and inwardly of the inner panel. 70

2. In a screened window structure embodying a rectangular frame having an upper and a lower cross member and provided with means forming an inner and an outer guideway, an upper panel mounted slidably in the outer guideway and adapted to close the upper part of the opening in the frame, a lower panel mounted slidably in the inner guideway and adapted to cover the lower part of the frame-opening, a spring actuated roller disposed adjacent to the upper cross member and inwardly of the inner guideway, and a flexible screen wound around the roller; a member connected to the upper panel and projecting inwardly therefrom across the inner guideway so as to form a stop for limiting the sliding movement of the lower panel, said last mentioned member being attached to the free end of the screen and adapted, during lowering of the upper panel, to unwind the screen from the roller and draw it downwardly in a rectilinear path inwardly of the inner guideway. 85

3. In a screened window structure embodying a rectangular frame provided with means forming an inner and an outer guideway, a pair of panels slidably mounted in the guideways and adapted normally to close the upper and lower parts of the opening in the frame and to be shifted towards each other into lapped relation to uncover said parts of the frame-opening, a spring actuated roller disposed opposite to one of the end members of the frame and inwardly of the inner guideway, a flexible screen having one end thereof wound around the roller, and a pair of guide devices for engaging the side margins of the screen, secured to the side members of the frame inwardly of the inner guideway; a member connected to the outer panel and projecting inwardly therefrom across the inner guideway, said last mentioned member being attached to the free end of the screen and adapted, during shift of the outer panel, to unwind the screen from the roller and move it in a rectilinear path between the guide devices. 110
